VIBRATORY STRUCTURE

Gustave A. Overstrom, Big Sur, Calif.

Application April 29, 1936, Serial No. 76,923

9 Claims. (Cl. 74—26)

This invention relates to vibratory structures, and, more particularly, to vibratory structures employed for the concentration, screening, or separation of various kinds of substances, such as ores, coal, rock, sand, oil well mud, slaughterhouse material, fibrous material, such as asbestos, cotton seeds, straw chaff in wheat, etc.

The object of the invention is to so combine and correlate a positive drive mechanism for imparting relatively inclined vibratory movements to an element upon which is received the material to be treated, with means to secure a differential action in at least one of said relative movements, and at the same time imparting 15 a tossing action to the material in the direction of its progression, and eliminating all bumping action.

A further object is to provide means, in a combination such as above set forth, to impart a tossing action to the material under treatment.

A further object is to provide means to impart the tossing action referred to in a direction trending away from one of the longitudinal edges of the vibratory element, and tending to separate 25 various portions of the material to be treated.

Still a further object is to provide in the combination referred to, a supporting structure for the vibratory element of such a nature as to impart 30 a curvilinear path of movement to the vibratory element.

A further object is to provide a structure of the nature referred to, which is simple, strong, rugged and durable, economical to manufacture, 35 efficient in operation, does not require expert supervision, and which is free from destructive and noisy vibration when in use.

In the handling of various materials for the separation or grading of the same by concentration 40 operation, a common practice heretofore has been to reduce the material to a size suitable for separation by floatation. However, where the material, such as ores, for example, is reduced to a very fine mesh, the losses of values, as well as the expense and troubles encountered, in the subsequent smelting operation, have 45 proven to be serious. To avoid these troubles, difficulties and losses, a more satisfactory and desirable practice is to separate out part of the material to be treated in coarser sizes than is required for the floatation treatment. This important and valuable result is attained in the combination of structural elements which constitutes the present invention.

Likewise, in screening and separating various

materials, by imparting relatively inclined vibratory movements to the screening element, through positively driven differential action, and imparting a tossing action to the material in the general direction of its progression, with elimination of all bumping action, I am enabled to secure a greater speed of progression of the material, to effect a more satisfactory separation, and to avoid objectionable noises and racking of vibrations imparted to the apparatus, its foundation supports, or the building in which the apparatus is used.

Again, in the case of screening operations with various materials, not only is a separation of the material effected, but, by the combined material 15 tossing action and positive differential drive, and the action of the inclined spring supports for the vibratory element, not only is the material caused to separate in its feeding progression, some portions moving in one line or path in the 20 general direction of feed, and other portions moving in a different line or path in the same general direction, but it separates in general grades along two adjoining boundary edges of the screen element. This is a most valuable result in that it enables me to effectively and satisfactorily screen such materials as asbestos, oil well mud, slaughterhouse materials, stem joints in wheat treatment, and various other materials.

In the accompanying drawings I have shown 30 a structure of vibratory apparatus embodying the principles of my invention, wherein—

Fig. 1 is a view in top plan of a vibratory structure embodying the principles of my invention.

Figs. 2 and 3 are vertical longitudinal sections on the lines 2, 2, and 3, 3, respectively, of Fig. 1, looking in the direction of the arrows.

Fig. 4 is a broken detail view, parts in vertical section, showing one of the inclined spring supporting legs for the vibratory structure.

Fig. 5 is a view in top plan, parts broken off, of a positive drive mechanism adapted for use in a vibratory structure embodying my invention.

Fig. 6 is a view partly in side elevation and partly in section on the line 6, 6, Fig. 5, looking in the direction of the arrows.

Fig. 7 is a view in elevation of the left-hand end of the structure as shown in Fig. 1.

Fig. 8 is a similar view of the right-hand end 50 of the apparatus.

Fig. 9 is a view in vertical transverse section along the line 9, 9, Fig. 1, looking in the direction of the arrows.

Figs. 10 and 11 are diagrammatic views in top 55

plan illustrating the operation of the vibratory structure embodying the principles of my invention.

The same part is designated by the same reference numeral wherever it occurs throughout the several views.

In a vibratory structure embodying my invention a suitable stationary supporting base frame 12, has mounted thereon a series of spring legs 13 or supports, indicated generally at 13. In practice these spring legs or supports are employed in pairs, one member of each pair being mounted upon each side bar of the supporting base frame 12. Any suitable means may be employed for securing the lower end of each spring supporting leg to the base frame side members. Various structures of spring supporting legs may be employed. A structure of spring leg support disclosed in my application Serial No. 44,921, filed October 14, 1935, may well answer the purposes of my present invention. In Fig. 4, I have shown this structure of spring or flexible leg support, consisting of one or more flat members 14, flanked on opposite sides at the respective ends thereof with a series of flat spring strips 15. Preferably the members 14, are of suitable non-crystalline flexible material such as wood, while the members 15, are preferably of spring steel. Each set of flanking members 15 is composed of flat elements placed flatwise against each other and of relatively different lengths, the longest member of each set bearing flatwise against a side face of a strip 14. At their lower ends each leg support is rigidly clamped in a bracket 16, suitable bolted to a side member of the base frame 12. The upper end of each flexible spring leg supporting structure is similarly rigidly secured in a bracket 17, bolted to a side member of a supporting frame 18, which is floatingly supported by said spring legs.

The leg supports 13, are mounted in vertically inclined position, the degree of inclination thereof with reference to a vertical line being such that in operation these legs do not reach or pass a vertical position. As indicated in Figs. 8 and 9, and diagrammatically in Fig. 10 the flat sides of the various pairs of leg supports are inclined with respect to each other, and with respect to the longitudinal dimension of the floating frame 18, and in increasing degree of inclination from end to end of said floating frame. In practice, and as indicated in Fig. 10, I prefer to so relatively incline the spring leg supports 13, and their flat sides or faces, that the planes of said faces, if prolonged as indicated in dotted lines at 19, see Fig. 10, will intersect at a common point in a line 20, at a distance of some fifty feet or more from the apparatus.

Vibratory movements may be imparted to the floating frame 18, by means of any suitable driving mechanism. In practice I prefer to employ for this purpose a positive drive mechanism. A satisfactory apparatus is shown consisting of a shaft 21, adapted to be driven in any suitable manner, as, for example, through a belt driven pulley 22, from any suitable source of power. The shaft 21, is journaled in bearings in a stationary casing 23, and carries an eccentric 24. A crank arm 25, actuated by the eccentric 24, is connected at its free end to a link 26, through a pivot pin connection 27, which, likewise, has pivotal connection with one end of a rod 28. The link 26, is pivotally connected by means of a pin 29, to a block 30, adjustably mounted within a housing 31, in the casing 23. The opposite end

of rod 28, is pivotally connected by means of a pin 32, to a block 33, adjustably mounted upon an arm 34, which forms a crank-arm upon a shaft 35, which is journaled in the side walls of the casing 23. Suitably clamped upon the end of shaft 35, which protrudes through a side wall of the casing 23, is an arm 36, formed with a cup-shaped bearing 37. Seated within this cup-shaped bearing is a ball member 38, carried by a stud 39, the other end of which carries a ball member 40, adapted to be received in a cup-shaped bearing 41, formed in a cross piece 42, which is connected to a convenient part of floating frame 18.

Mounted and held upon, to move with, the floating frame 18, is an element 43, which, for convenience, I shall call a deck. Where the apparatus is to be used as a concentrator, the deck is ordinarily covered with linoleum, and, usually, with rifles, as indicated at 44, extending in the general direction of the length of the deck. Where the apparatus is to be used as a screen the deck is covered over with a suitable screen cloth or a perforated plate. Also, if desired, and as shown, the deck 43 has hinged connections adjacent one of the longitudinal sides thereof with the floating frame 18, as indicated at 44, see particularly Figs. 2, 7, and 8. Adjacent the opposite side member of the floating frame 18, is mounted a member 45, having a series of inclined sections 30 constituting adjusting wedge blocks upon which bear suitable cross members 46, forming parts of the deck frame. By suitably adjusting endwise the connected series of wedge members 45, the angle of inclination of the deck may be adjustably varied as desired and according to the character of material to be operated upon. An adjusting screw 47 serves to effect the desired tilting adjustment of the wedge members 45.

Where the apparatus is employed for use as a concentrator a combined material feed and wash water trough 48, is ordinarily mounted along the upper side edge of the deck frame.

The operation of the apparatus is very simple. When the power driven shaft 21, is driven, the rod 28, by reason of its pivotal connection with link 26 and crank arm 25, is given a longitudinal reciprocation, as the angle which the members 26, 28 make with each other is varied through the action of crank arm or pitman 25. This longitudinal reciprocation of rod 28, rocks the arm 34, thereby axially rocking shaft 35, and with it the crank arm 36. By the engagement of the cup-shaped seat 37, at the free end of arm 36, with the ball member 38, a pull towards the left (see Fig. 6), is exerted upon the floating frame 18, through the stud 39, bearing member 40, and the bearing 41. This is the action which takes place when rod 28, is projected endwise towards the right. This movement of floating frame 18, is opposed by the spring supporting legs 13, the tension of which is exerted tending to move the floating frame 18, towards the right. When rod 28, is moved towards the left an opposite action takes place. The floating frame in that case is moved towards the right by the tension exerted thereon by the spring legs. The deck is not, nor is the floating frame, subjected to any bumping action tending to cause noise, or to rattle the frame structure of the apparatus or its foundation supports.

It will also be seen that the apparatus which imparts vibratory movements to the deck member is positive in its differential motion movements in both directions, the movement in one

direction being directly applied by power from the drive shaft and that in the opposite direction being accomplished by the reaction of the spring leg supports. If there were nothing else to be considered, the reciprocatory movements of the deck would be uniform in extent of movement in both directions, as modified by the differential action. In that case the movement imparted to the material would be along a straight line of progression parallel with the deck surface and in line with the movements imparted to the deck. This would result in a failure to attain satisfactory results, whether for concentrating or screening operations, as I have hereinbefore pointed out, and a failure to properly separate the various elements of the material. However, by combining with the positively acting differential drive the relative arrangement of the spring leg supports, in the manner as hereinbefore described, and the relatively displaced angular relation of the faces or flat side surfaces thereof from end to end of the deck, an entirely new and exceedingly important and valuable result is accomplished, namely, the material is subjected to a vertical tossing movement delivered in the general direction of feed progression, while at the same time an arcuate line of travel is imposed upon the vertically tossed material. It is to be understood that this result is contributed to by the mounting of the spring leg supports in vertical inclined positions. But the inclination of the spring leg supports must be such that in the operation of the apparatus, said leg supports should never be permitted to pass beyond a vertical position.

The action of the apparatus when in operation under the condition of inclination of the spring leg supports, and of the relatively displaced angular disposition of the flat sides or faces of said leg supports, is indicated diagrammatically in Figs. 10 and 11. Instead of the line of feed progression of the material along the surface of the deck member of the apparatus being a straight line in parallel relation to the line of application of the power for, and parallel with, the lower edge of, the deck, said line of progression will be along a curved line, as indicated at 50, Fig. 10, which carries the material progressively away from the lower edge of the deck element, as well as towards the far end of the deck. In the case of water separation this action leaves a zone or area of deck surface indicated roughly at ACF, for the separation of slime portions of the material and their discharge along the portion FC of the deck edge, while the zone or area ACDB for the separation of the lighter and larger solid portions of the material and their discharge along the portion CD of the lower edge of the deck. The area or zone ADEB is utilized for separating out the medium heavy portions of the material and their discharge along the end portion DE of the deck. The area or zone AEG is utilized for separating the portions of material of the heaviest specific gravity, and their discharge along the portion EG of the end of the deck.

In Fig. 10 I have diagrammatically indicated the action and results attained when the spring leg supports are inclined both vertically and in angular relation with respect to each other, whereas in Fig. 11 I have indicated the action and results attained when the material is not subjected to either a tossing motion nor to a feed progression away from the lower side or

edge of the deck. By comparing the illustrations of Figs. 10 and 11, it will be seen that the discharge length CD, Fig. 10, is substantially double that of the discharge length C'D', Fig. 11. This means that with the arrangement and operation indicated in Fig. 10, that is, as embodied in my present invention, I am enabled to secure a much greater capacity and a more perfect separation. In this connection it is to be noted that with a straight motion action, as indicated in Fig. 11, the zone or area B'E'G' is not utilized for any appreciable separating action, whereas the zone or area BEG, Fig. 10, is fully utilized.

If desired, the housing in which the positive differential drive mechanism is mounted, may be filled with a lubricant so as to lubricate the various joints of said mechanism.

It will be understood that various modifications and changes in the details of structure of the apparatus may be made without departure from the spirit and scope of my invention.

But, having now set forth the objects and nature of my invention, and a structure embodying the principles thereof, what I claim as new and useful, and of my own invention, and desire to secure by Letters Patent is:

1. In an apparatus of the nature described, a deck to receive the material to be treated, a frame carrying said deck, a positive differential drive mechanism connected to said frame to impart vibratory movements thereto, in combination with spring legs for floatingly supporting said frame, said legs being constructed to yieldingly resist the action of the positive drive mechanism and so disposed angularly relatively to each other as to cause a tossing action to be imparted to the material carried by the deck, and in a direction inclined to the line of reciprocatory movements imparted to the deck.

2. In an apparatus of the nature described, a deck to receive the material to be treated, positively acting differential drive mechanism to impart vibratory movements to said deck, flat spring supporting legs for said deck, said supporting legs being disposed with their flat faces in different angular relations with respect to each other.

3. In an apparatus of the class described a frame, a deck carried by said frame, resilient flattened supporting legs for said frame, said supporting legs being arranged in increasingly angular relation to each other from end to end of said frame and a positive differential drive mechanism connected to said frame.

4. In an apparatus of the nature described, a frame, spring leg supports for said frame arranged in successive pairs and having flat sides or surfaces, a positive differential drive mechanism connected to said frame, said spring supporting legs operating to resist the action of said drive mechanism and having their flat surfaces inclined to the line of movement imparted by the drive mechanism and a deck carried by said frame.

5. In an apparatus of the nature described, a frame, a deck carried thereby to move therewith a positive differential drive mechanism connected to said frame for imparting vibratory movements thereto and vertically inclined spring leg supports for said frame, arranged in different angular relations to the line of reciprocatory movement of the drive mechanism to impart a tossing action transverse to the line of reciprocatory movement to material carried by the deck.

6. In an apparatus of the class described a positive differential drive mechanism for imparting vibratory movements thereto, including freely engaging ball and socket members, and spring supports for said deck, said spring supports having flat faces or sides disposed in angular relation with respect to the line of reciprocatory movements imparted to the deck.
7. In an apparatus of the class described, a positive differential drive mechanism for imparting vibratory movements thereto, including a universal joint connection to said deck, and spring supports for said deck, said supports having flat faces or sides disposed in angular relation to the line of reciprocatory movements imparted to the deck.
8. In a separating apparatus a deck, a floating frame carrying said deck, said floating frame being yieldingly supported by continuously tensioned spring legs, and a positive differential drive mechanism connected to said floating frame to one side of the transverse center thereof, and said spring legs being arranged to impart tossing movements to the material carried by said deck in lines of movement relatively inclined to the line of movement of the drive mechanism.

mechanism flexibly connected to said floating frame to impart differential movement thereto, said drive mechanism being connected to the floating frame so as to place said spring legs under tension, and said spring legs being arranged 5 to impart tossing movements to the material carried by said deck in lines of movement relatively inclined to the line of movement of the drive mechanism.

9. In a separating apparatus a deck, a floating frame carrying said deck, said floating frame being yieldingly supported by continuously tensioned spring legs, and a positive differential drive mechanism connected to said floating frame to one side of the transverse center thereof, and 15 said spring legs being arranged to impart tossing movements to the material carried by said deck in lines of movement relatively inclined to the line of movement of the drive mechanism.

GUSTAVE A. OVERSTROM. 20
